UNITED STATES PATENT OFFICE.

FRITZ HUELSENBECK, OF NEWARK, NEW JERSEY, ASSIGNOR TO JERSEY BISCUIT CO., OF NEWARK, NEW JERSEY, A CORPORATION OF NEW JERSEY.

DESIGN FOR A FRONT PANEL FOR BOXES.

No. 38,648.

Specification for Design.

Patented July 2, 1907.

Application filed May 21, 1907. Serial No. 374,955. Term of patent 14 years.

To all whom it may concern:

Be it known that I, FRITZ HUELSENBECK, a citizen of the United States, residing at Newark, in the county of Essex and State of New Jersey, have invented a new, original, and ornamental Design for a Front Panel for Boxes, of which the following is a specification, reference being had to the accompanying drawing, forming part thereof.

The figure is a front view of the front panel for boxes.

What I claim is:—

The ornamental design for a front panel for boxes, as shown.

FRITZ HUELSENBECK.
